UNITED STATES PATENT OFFICE.

ED SCOTT, OF MOUNDS, OKLAHOMA.

BLOTTER FOR CHECK BOOKS.

Application filed November 18, 1922. Serial No. 601,934.

To all whom it may concern:

Be it known that I, Ed Scott, a citizen of the United States, residing at Mounds, in the county of Creek and State of Oklahoma, have invented new and useful Improvements 5 in Blotters for Check Books, of which the following is a specification.

This invention contemplates the provision of a check pad holder, which together with 10 the check pad is capable of being folded in a small compact article so that it can be conveniently carried on the person of the user.

One of the objects of the invention is to associate with the holder, a blotter including 15 a foldable section, which when extended affords the blotter a size to extend across the entire length of the check and its stub, but which section when folded permits the holder and pad to be arranged in compact form.

20 The nature and advantages of the invention will be better understood when the following detailed description is read in connection with the accompanying drawings, the invention residing in the construction, 25 combination, and arrangement of parts as claimed.

In the drawings forming part of this application, like numerals of reference indicate similar parts in the several views, and 30 wherein:

Figure 1 is a perspective view of the holder partly opened.

Figure 2 is a longitudinal sectional view taken on line 2—2 of Figure 1.

35 Figure 3 is a plan view showing the blotter extended.

Figure 4 is a side elevation of the holder completely folded.

40 Referring to the drawings in detail, A indicates a holder which embodies an intermediate section 10 and opposed end sections 11 and 12 respectively. The sections are adapted to be folded one upon the other to produce a comparatively small article, and held 45 in this position by means of a closure flap 13 which forms a continuation of the end section 12, and adapted to be folded over the intermediate section 10 and secured thereto in any suitable manner as indicated at 14. The 50 check pad is of well known construction and indicated at 15, the card board back at 16 being reduced in size, and slid into a pocket 17 forming part of the section 11. The com-

bined length of the sections 10 and 11 is just slightly greater than the length of the check 55 including the stub, so that when the holder is opened, it provides a proper support for the check.

Associated with the section 12 is a blotter preferably including two parts indicated at 60 18 and 19 respectively and which parts are arranged in end to end relation as shown. The part 18 is secured to the inner side of the section 12, which section is formed to provide a pocket 20. The other part 19 of 65 the blotter is secured to a flexible strip 21, a portion of which is arranged within the pocket 20 and secured to one wall thereof, so that the strip 21 provides a hinge which permits the part 19 of the blotter to be folded 70 upon the part 18 or extended in end to end relation with the latter when its use is desired. When the section 19 is extended for use, the combined lengths of the respective sections of the blotter is slightly greater 75 than the length of the check and stub therefor, so that the entire arrangement of the check is covered by the blotter incident to the use of the latter. As above stated the article can be folded and materially reduced 80 in size, and thereby permitted to be conveniently carried in the pocket of the user. For this purpose, it is only necessary to arrange the part 19 of the blotter upon the part 18, the section 11 upon the section 10 85 of the holder and then arrange the section 11 upon the section 19 of the blotter. The closure flap 13 is then folded over on the section 10, and secured thereto in any suitable manner.

90 While it is believed that from the foregoing description, the nature and advantages of the invention will be readily apparent, I desire to have it understood that I do not limit myself to what is herein 95 shown and described and that such changes may be resorted to when desired as fall within the scope of what is claimed.

What is claimed is:

100 A check pad holder including an intermediate section and end sections, adapted to be folded one upon the other, pockets formed by each end section, the back of the check pad being slipped in the pocket of one end section, a blotter including two parts, one 105 of said parts being attached to the other end

section and fixed relatively thereto, the other part of the blotter being arranged in end to end relation with the fixed part, and movable with relation thereto, a flexible connection between the movable part of the blotter and the adjacent end section, whereby said movable part is adapted to be extended for

use or folded upon the fixed part of the blotter, and a closure flap carried by the latter mentioned end section and adapted to be secured to the intermediate section.

In testimony whereof I affix my signature.

ED SCOTT.
